DESCRIPTION

U.S. PATENT DOCUMENTS

D389,798 S * 1/1998 Ma et al. D12/192

D431,220 S * 9/2000 Wyszogrod et al. D12/192

D433,362 S * 11/2000 Wyszogrod et al. D12/192

D480,671 S * 10/2003 Pfeiffer et al. D12/192

FIG. 1 is a front view of a dashboard having an electronic display, showing my design;

FIG. 2 is a right side perspective view thereof; and,

FIG. 3 is a left side perspective view thereof.

The broken line showing of parts of the drawings is included for the purpose of illustrating use and environment and forms no part of the claimed design.
